UNITED STATES PATENT OFFICE

WILLIAM F. PRINGLE, OF OAKLAND, CALIFORNIA, ASSIGNOR OF ONE-THIRD TO JAMES P. CALLAHAN AND ONE-THIRD TO DANIEL J. NEE

CIGARETTE EXTINGUISHER

Application filed June 22, 1929. Serial No. 372,980.

This invention relates to cigarette extinguishers of the type wherein a perforated cup mounted above a water well is depressed to raise water to the well for extinguishing a cigarette or cigar, and the objects of the invention are to provide improvements in such devices whereby they are cheaper to manufacture, easier to operate, and not so liable to leak. Other objects appear in the specification to follow and in the drawings accompanying this application.

In the drawings Fig. 1 is a perspective view of my improved extinguisher as assembled complete with a butt and burnt match receptacle on a common wall bracket.

Figs. 2, 3, 4, and 5, are respectively vertical cross sections of various modifications in the internal construction of the extinguisher portion of my assembly.

20 In further detail 1 is the sheet metal bracket secured to the wall 2 which may be any portion of an automobile or car body where-with the device finds its most important use, 3 is the butt receptacle and 4 the extinguisher 25 both being cylindrical sheet metal receptacles suspended on enlarged shoulders through openings in the bracket.

The butt receptacle requires no description further than to say that it has a detachable 30 funnel like portion 3' for guiding the waste matter to the receptacle and preventing its accidental dislodgment through jouncing of the vehicle in which the device is installed.

The extinguisher receptacle 4 is surmount- 35 ed by a funnel-shaped cup 5 provided with a perforated bottom 6 and secured firmly to an upwardly arched soft rubber diaphragm 7 so that it may be depressed and the resiliency of the diaphragm will always restore it to its 40 elevated position.

The diaphragm is clamped at its outer border against the upper edge of the receptacle by means of a flange ring 8 which may be either screwed or pushed tightly over the rim 45 of the receptacle, and the central portion of the diaphragm is provided with a central opening so as not to cover the perforations in the bottom of the cup and is clamped to the cup by various means indicated in the modi- 50 fications shown in Figs. 2 to 5.

In Fig. 2 the cup is guided for vertical movement by means of a dependent tube 9 loosely straddling a guide pin 10 or rivet shank fixed to the bottom of the cup. The upper end of the tube 9 being outwardly flared and secured as by solder or any other means to the bottom of the cup, and the diaphragm pinched between the bottom of the cup and a ferrule 11 tightly forced over the tube 9. This ferrule may be soldered or otherwise secured if desired, but a simple press fit will never come off unless desired to renew the diaphragm and when it may be forcibly pulled by engagement of a puller over a lower flange 12 provided for that purpose.

In use water is kept in the receptacle as shown at 13 and upon depressing the cup either with the finger or the cigarette the diaphragm forces the imprisoned air downward and raises the water in tube 9 until it appears in the cup so that the cigarette may be extinguished.

In the modification shown in Fig. 3 tube 9 is provided at its lower end with an inverted soft rubber cup 14 normally clearing the bottom of the cup and which when forced downward by depressing the upper cup 5 forces the water imprisoned under the cup upward through a passage in the shank of the rubber cup and tube 9 into the extinguishing cup 5. In this construction the upper cup is also guided for vertical movement.

In Fig. 4 the interior mechanism is omitted and replaced by a sponge 15 the action of which when impregnated with water is self-evident.

In Fig. 5 the tube 9 is provided at its lower end with an enlarged plunger 16 slidably fitting within an auxiliary well 17 provided with a minute aperture at 18 for ingress of water at the bottom. By depressing the cup 5 the water in auxiliary well 17 is forced upward into the cup 5 before it can escape from the small hole 18.

The design of Figs. 3 and 5 positively limit the amount of water forced into the upper cup.

In any of the designs the receptacle is easily cleaned by prying off, or unscrewing as the

case may be, the outer clamping ring 8 which clamps the diaphragm to the upper edge of the receptacle.

While I prefer a soft rubber diaphragm it is manifest that other resilient material will work or even a thin metal diaphragm, and I therefore claim:

10. 1. A cigarette extinguisher comprising a well, a flexible diaphragm clamped to the top of the well, a cup carried by the diaphragm provided with a perforated bottom open to the underside of the diaphragm, and means within the well adapted to force water from the well upward into the cup upon depressing the same.
15. 2. A cigarette extinguisher comprising a well, a flexible diaphragm clamped to the top of the well, a cup carried by the diaphragm provided with a perforated bottom open to the underside of the diaphragm, and means within the well adapted to force water from the well upward into the cup upon depressing the same, and means for guiding the cup and diaphragm for vertical movement.
20. 3. A cigarette extinguisher comprising a well, a flexible diaphragm clamped to the top of the well, a cup carried by the diaphragm provided with a perforated bottom open to the underside of the diaphragm, a dependent tube secured to the underside of the cup embracing the perforations, and means within the well guiding the lower end of the tube for vertical movement.
25. 4. A cigarette extinguisher comprising a well, a flexible diaphragm clamped to the top of the well, a cup carried by the diaphragm provided with a perforated bottom open to the underside of the diaphragm, a dependent tube secured to the underside of the cup embracing the perforations, and pumping means within the well guiding the lower end of the tube and for forcing water from the well up the tube upon depressing the cup.
30. 5. A cigarette extinguisher comprising a well, a flexible diaphragm clamped to the top of the well, a cup carried by the diaphragm provided with a perforated bottom open to the underside of the diaphragm, and means within the well adapted to force a measured quantity of water from the well upward into the cup upon depressing the same.

WILLIAM F. PRINGLE.
